United States Patent Office.

GEORGE W. BELL AND GEORGE W. FULMER, OF HINCKLEY, OHIO.

Letters Patent No. 76,881, dated April 21, 1868.

IMPROVEMENT IN HORSE AND CATTLE-POKE, &c.

The Schedule referred to in these Letters Patent and making part of the same.

TO ALL WHOM IT MAY CONCERN:

Be it known that we, GEORGE W. BELL and GEORGE W. FULMER, of Hinckley, in the county of Medina, and State of Ohio, have invented certain new and useful Improvements in Poke for Horses, Cattle, &c.; and we do hereby declare that the following is a full and complete description of the same, reference being had to the accompanying drawings, making a part of this specification, in which—

Figure 1 is a side view.

Figure 2 is a top view.

Figure 3 is an end view.

Like letters of reference refer to like parts.

In the views, A represents the yoke, secured to the poke B, in the following manner: C, fig. 2, is an adjustable slide, that surrounds the poke B, and is held to the same by means of the thumb-screw α . The ends of the yoke A are pivoted to shafts extending out from said slide, and secured by screws α' , as shown.

Secured on the end of the poke B is the head D. Over this head is hung, on the pins b, the plate E. This plate is also supported by the spring F.

I are spikes or points, secured in the edge of the plate E, and extending down through holes e, in the head, the purpose of which will be referred to hereafter.

This poke is placed on the horse, the yoke over its neck, with the head D next to its breast.

As the horse goes near a fence, the end of the poke will strike against said fence, and thus throw the head D up against the yoke A, which causes the plate to be pressed down on to the head D, and thus push the points through the holes in said head into the breast of the animal. As soon as the end of the poke is removed from the fence, the spring F will force said plate up in position again.

G G are springs, which may be used in place of the spring F, which are secured to a pin in the poke, and the end connected to the plate E.

By means of this adjustable slide, the poke can be adapted to a large or small animal. For smaller ones, the yoke is moved nearer to the head D.

What we claim as our improvement, and desire to secure by Letters Patent, is—

The adjustable slide C, in combination with the yoke A, poke B, and head D, in the manner as and for the purpose set forth.

GEORGE W. BELL,
GEORGE W. FULMER.
